United States Patent Office.

SAMUEL S. BENT, OF PORTCHESTER, NEW YORK.

Letters Patent No. 78,857, dated June 16, 1868.

IMPROVEMENT IN HENS' NESTS.

The Schedule referred to in these Letters Patent and making part of the same.

TO ALL WHOM IT MAY CONCERN:

Be it known that I, SAMUEL S. BENT, of Portchester, in the county of Westchester, and State of New York, have invented, made, and applied to use, a certain new and useful Improvement in Hens' Nests; and I do hereby declare the following to be a full, clear, and exact description of the said invention, reference being had to the annexed drawing, making part of this specification, wherein—

Figure 1 is a plan of said hen's nest, and

Figure 2 is a vertical section of the same.

Similar marks of reference denote the same parts.

Hens' nests are liable to become filled with vermin, greatly to the injury of the young chicken; besides this, a person going through the coop to gather up the eggs from the nests, disturbs the hens that are setting.

The object of this invention is to furnish a cleanly nest in which vermin cannot remain, and at the same time allow the nests to be inspected and eggs removed, as desired, without going through the coop itself.

In the drawing, *a* is the bottom, *b* the sides, *c* the back end, and *d* the front end of a cast-iron nest, the angles of which are curved, so that the nest can be easily kept clean.

Holes are to be provided in the back end *c*, by which the nest can be supported upon nails or hooks *e*, driven into the partition *f*, which may be either wood-work or plaster.

The shelf *p* is provided upon the under front portion of the nest, upon which the hen can light when jumping or flying to the nest, and the front edge of the nest is rounded or formed with a rib, *g*, so that a foot-hold is given to the hen in stepping into the nest, and hence she will not be likely to disturb or break the eggs or injure the chickens.

I extend the sides *b* up in the form of open work, as at *h*, which prevents the hens disturbing each other in adjoining nests, and also allows a free ventilation, particularly where the nests are placed in ranges side by side, and also one over the other.

After a nest has been used in hatching a brood of chickens, it should be taken down, brushed out, and dipped into lime-water.

In order to examine the nests from the outside of the chicken-coop, the nests are to be hung against the partition *f* in the poultry-house, and openings provided for the movable door or window *k*, that is to be of a sufficient size for inserting the hand into the nest, and I provide a small opening at *i*, in the door or window, by which the contents of the nest can be observed without opening the door or window *k*. I have represented a piece of glass in said opening *i*.

The door *k* is shown as sustained by the metal frame *l*, that passes through the partition *f*, and is screwed to the nest, and the said door or window *k* swings on the hinge-lugs *o*, but this construction might be varied to suit the convenience of the attendant or the construction of the hen-house.

This improved nest may be used for other kinds of poultry as well as chickens.

What I claim, and desire to secure by Letters Patent, is—

1. A metallic hen's nest, formed with rounded corners, and with the rib *g* at the front end, as and for the purposes specified.

2. The lighting-shelf *p*, in combination with metallic hen's nest, formed as aforesaid.

3. The side partitions *h*, combined with the metallic hen's nest, to separate one nest from another, as and for the purposes set forth.

4. A movable door or window, *k*, in combination with the frame and hen's nest, to give access to the same from outside the coop, substantially as set forth.

In witness whereof, I have hereunto set my signature, this 11th day of May, 1868.

Witnesses:

CHAS. H. SMITH,

GEO. T. PINCKNEY.
